CLAIM

The ornamental design for caged skewed caster legs, as shown and described.

DESCRIPTION

FIG. 1 is a perspective view of the caged skewed caster legs showing my new design;

FIG. 2 is a right side elevational view thereof;

FIG. 3 is a front side elevational view thereof;

FIG. 4 is a left side elevational view thereof;

FIG. 5 is a rear elevational view thereof;

FIG. 6 is a top elevational view thereof; and,

FIG. 7 is a bottom elevational view thereof.

The broken line showing of a base and wheel is for illustrative purposes only and forms no part of the claimed design.
